UNITED STATES PATENT OFFICE.

JENNIE HELLAMS SWEENEY, OF UNION, SOUTH CAROLINA.

DESIGN FOR A MEDAL OR BADGE.

56,083.

Specification for Design. Patented Aug. 10, 1920.

Application filed May 3, 1920. Serial No. 378,698. Term of patent 14 years.

To all whom it may concern:

Be it known that I, JENNIE HELLAMS SWEENEY, a citizen of the United States, residing at Union, in the county of Union and State of South Carolina, have invented a new, original, and ornamental Design for a Medal or Badge, of which the following is a specification, reference being had to the accompanying drawings, forming a part thereof.

The figure is a front elevation of the medal or badge showing the new and ornamental design.

I claim as my invention:

The ornamental design for a medal or badge, as shown.

In testimony whereof, I affix my signature.

JENNIE HELLAMS SWEENEY.
